ABSTRACT OF THE DISCLOSURE

A tester for tennis court surfaces, such as textile surfaces, in which a tennis ball is fired by compressed air through a tube into a chamber that is painted flat black on the inside. The tennis ball strikes the surface to be tested in front of a camera. Two flashing strobe lights are provided so that the camera takes a series of multiple exposures of the tennis ball. The angle of the exposures of the tennis ball on the way down and on the rebound can be measured in photographs and is a measure of the surface to be tested.

BACKGROUND OF THE INVENTION

Tennis court surfaces present a considerable problem. If a surface is very smooth, for example an asphalt court or a smooth concrete court, there is a tendency for a hard hit ball, such as, for example, a hard serve, to skid some, in other words to rebound at a smaller angle than that at which it strikes the court. This makes it difficult to return such a ball and is generally considered undesirable. Clay courts and even some grass courts have a sufficient coefficient of friction so that skidding of the ball is minimized. However, such courts present problems in slow drying after a rain storm, maintenance, and the like. However, for expert play the smoother asphalt or very smooth concrete courts are not satisfactory because the surface has too low a coefficient of friction. In recent years various fabrics, such as tufted, woven, needle punched, and the like, or extruded or molded materials have been used as covering for courts which would otherwise show inadequate coefficients of friction. The carpeting thus produced is, of course, cemented onto the court surface, such as asphalt. A typical covering or carpeting is described in the co-pending application of Depoe and Lombardi, Ser. No. 24,681 filed Apr. 1, 1970, and assigned to the assignee of the present invention. This improved surfacing also provides for rapid drain after a rain storm.

Particularly with textile or other surfaces which are to be cemented on the court it is important that the coefficient of friction be as near ideal as possible. Until the present, the only way of determining if a surface had the proper playing characteristics was to rely on player evaluation, which is a subjective variable. An accurate, simple tester which can test the surface or a corresponding sample is therefore needed, and it is with an improved form of tester that the present invention deals.

SUMMARY OF THE INVENTION

The present invention provides exact information which can be used in comparing different surfaces being tested. The invention records the flight of a tennis ball in multiple exposure on film when the ball is fired at a definite angle and a definite speed and rebounds from a sample of the surface to be tested. The firing of the ball is through an

2

inclined tube by means of compressed air or other charge which can be maintained accurately to give a constant velocity. The tube projects into a housing painted a flat black on the inside, with a recording camera, such as a Polaroid camera, passing through a wall of the chamber at the point where the ball strikes the surface to be tested. Flashing strobe lights, usually two, result in a series of multiple exposures of the tennis ball, and from photographs the exact angle of rebound, which is the most important factor, can be measured. Also, another feature of the surface, namely rebound speed, can be measured on the photograph because the diameter of the tennis ball is known and the exact frequency of the flashing light permits reliable calculation of speed. For example, if, as is often the case with a good surface, the ball is moving more rapidly in its trajectory before it strikes the surface than it does on rebound, the multiple exposures will show the ball images further part on the way toward the surface than on the rebound. It is thus possible to measure all of the necessary characteristics of a surface from a comparatively small sample with precision and accurate reproducibility. As the tennis ball is white, it photographs in each flash, whereas the background, which is flat black, remains dark.

If the ball rebounded back off another wall of the housing of the tester it might show in the photograph unless there was a precisely timed shutter opening and closing, which can be provided and which is desirable in certain preferred embodiments of the invention. Therefore, it is desirable to keep a rebounded ball from coming back into the area where photographing takes place and this can be effected by providing a slot through which the ball rebounds into a ball recovery chamber which retains the ball and does not permit it to bounce back into the area where multiple photography is taking place. This is a preferred modification, although the device works perfectly well without a ball recovery chamber if there is a sufficiently precise timing of the camera shutter. Theoretically, of course, a slot through which the rebounding ball could pass would be able to permit its return, but the slot is accurately positioned with respect to the rebound and when the ball goes into a chamber through the slot and bounces back, chances of its striking the slot at exactly the right angle are practically negligible.

One or more flashing strobe lights are mounted inside of the black enclosure or they may be outside, on its top, and flashing through openings in the enclosure into which the strobe lights fit substantially light-tight. Both modifications have advantages. The mounting of the strobe lights inside the enclosure brings them quite close to the trajectory of the tennis ball on its initial course and rebound and, therefore, sharp multiple photographs can be obtained with minimum intensity of the flashing strobe lights. On the other hand, if the strobe lights are mounted on top of the enclosure, while they have to be somewhat more intense because they are further away from the two trajectories of the tennis ball, the mounting permits servicing and simplifies connecting the strobe lights to their source of electric pulses. The lights are, of course, positioned to illuminate the portion of the surface being tested. It is an advantage of the invention that the particular choice of strobe light mounting can be chosen for the best compromise.

The strobe lights themselves are of standard design, and so in the further description and in the drawings their

electrical connections are not shown as they are not changed by the present invention, except of course that the dimensions of the tester determine lengths of supply cables.

As the frequency of flashing should be maintained constant so that speed of rebound as well as angle can be measured, it is desirable to provide accurate timing, which can be done with conventional solid state electronics which deliver accurately timed trigger pulses to relays, such as silicon controlled rectifiers, which permit pulses of high voltage and high current to the flashing lights. The lights themselves are, of course, of conventional design, utilizing gaseous discharge tubes.

Since it is desirable to fire the tennis ball each time with either the identical speed or with speeds which can be adjusted and maintained constant, it is preferred to use as the motive force a compressed air source of comparatively large capacity with a suitable trigger valve. Pressure can be varied with a pressure controlling valve in well known manner. These elements, therefore, will be described and shown in the drawings in diagrammatic form.

The compressed air or other gas container may be outside the tester proper, with a suitable flexible conduit connecting to the ball discharge tube, or it may be mounted on one wall of the container itself. Other sources of motive power for the tennis ball may also be used, such as explosive cartridges, compressed springs, and the like. However, the use of compressed air is so simple and reliable that it constitutes the preferred embodiment and will be the one which is described in detail below, although it should be understood that the invention is not limited to the particular means which impart a definite predetermined velocity to the tennis ball.

The nature of the camera photographing the flight of the ball is not critical and any type of camera may be used. However, a Polaroid camera, which permits inspecting a photograph very shortly after it has been taken, presents so many advantages that it is greatly preferred.

BRIEF DESCRIPTION OF THE DRAWINGS

FIG. 1 is a semi-diagrammatic section through a surface tester;

FIG. 2 is a vertical elevation, partly broken away, at right angles to FIG. 1;

FIG. 3 is a multiple exposure photograph of a tennis ball striking and rebounding from a smooth surface, and

FIG. 4 is a similar illustration where the surface has a desirably high coefficient of friction.

DESCRIPTION OF THE PREFERRED EMBODIMENT

FIG. 1 shows an enclosure, open at its bottom, designated 1. The inside of the enclosure is painted matte black, and the enclosure is shown set down on the flat tennis court surface. The portion of the tennis court being tested is designated 3, which is opposite a camera 2 with lens 15, which can be seen in FIG. 2.

A pair of gaseous discharge strobe lights 4 are mounted underneath the top of the enclosure. As these lights are conventional, they are shown in diagrammatic form. Supply of powerful high voltage electric pulses to the flashing lights come in through conventional cables, which are shown symbolically as a pair of wires 16. The rest of the strobe lamp supply is not shown because it is not changed by the present invention. However, the supply should permit flashing at predetermined frequencies, for example 20,000 to 25,000 flashes per minute.

From the left a ball firing tube 5 is shown entering at an angle through a wall 9. The tube has a ball loading chamber 6 and is connected by a tube with a compressed air supply 7, preferably having a definite volume, provided with a regulating valve 13. When a ball is loaded into the tube and the loading chamber closed, a trigger 12 introduces the compressed air and is preferably ac-

tuated for a sufficient time to introduce a definite predetermined volume of air. The ball is projected at 60 or more feet per second through the tube. The ball is shown at 8 just before it strikes the surface 3. After striking it, it rebounds, as indicated by the arrow, passing through another slot 10 into a ball recovery chamber from which the ball can be removed through an opening 11 with a suitable closure to prevent entering light during the testing.

The surface 3 is under the housing 1 and a tennis ball is loaded into the ball loading chamber 6. The trigger 12 is then actuated and a blast of compressed air projects the ball through the tube 5, striking the surface 3, and rebounding into the ball recovery chamber as shown. The trigger 12 can start the strobe lights 4 flashing and open the camera shutter 15 if desired. It is perfectly possible to operate by opening the camera shutter and starting the strobe light tubes with a manual switch. However, this results in some additional light even though the walls of the enclosure are black and the tennis ball has moved through its path. The particular modification to be chosen depends on a balance between darker background as against the additional equipment for opening the camera shutter and/or starting the lights.

Various surfaces can be tested, for example a sample of hard board surface which has a coefficient of friction similar to that of an asphalt surface of an asphalt tennis court. Various textile surfaces can also be tested, on or off a court.

FIGS. 3 and 4 show two photographs, FIG. 3 being a rebound from smooth hard board and FIG. 4 from a tennis court surface of needle-punched fabric. It will be seen that the multiple exposures in FIG. 3 represent a fairly flat angle which can be measured on the photograph with a suitable movable protractor, whereas in FIG. 4 the carpet surface results in a greater angle of rebound and also a marked slowing down, which is shown by the fact that the multiple exposures of the tennis ball are of the same dimensions in FIG. 3, whereas in the rebound they are more close together as the speed of the ball has been slowed down.

Typically the rebound angle in FIG. 3 is between 28° and 29° and in FIG. 4 between 36° and 37°. The speed of rebound is about 48 feet per second in FIG. 3 and about 37 feet per second in FIG. 4. This latter figure shows a surface that has substantially ideal coefficient of friction characteristics and which compares to the best, well maintained, dry, clay courts.

The tester of the present invention is not only useful in testing various new surfaces but can be used for monitoring batches of the same design of textile to determine if they are uniform and to reject any bad batches.

I claim:

1. A tester for tennis court surfaces comprising in combination,
  - (a) an open-bottom enclosure having a top, two ends and two side walls, the inside of the enclosure being a non-reflective black and the bottoms of the side and end walls being even so that the enclosure can rest on a flat surface without permitting the entrance of extraneous light,
  - (b) a recording camera in a side wall at about the middle thereof but near the bottom,
  - (c) an inclined tube of tennis ball dimensions in one end wall and inclined so that a projected tennis ball strikes a surface adjacent the camera lens,
  - (d) means for loading a tennis ball into the upper end of the tube and closing it off,
  - (e) trigger actuated means for imparting a reproducible high velocity to the tennis ball in the tube, and at least one flashing strobe light at the top of the enclosure positioned to illuminate the flat surface to be tested, means for actuating the strobe light at a frequency to produce multiple exposures of the tennis ball during both projection and rebound from the

surface, whereby on actuation of the trigger the tennis ball is projected against the surface and rebounds and the trajectories are photographed by the camera in multiple exposure during each trajectory, the number of multiple exposures in each trajectory being inversely proportional to the speed of the tennis ball through the trajectory.

2. A tester according to claim 1 having, at the end opposite the ball introducing tube, a ball recovery chamber separated from the center part of the enclosure of a slot of dimensions permitting a rebounding tennis ball to pass therethrough, whereby the rebounding ball is prevented from moving back into the zone of the flashing lights.
